UNITED STATES PATENT OFFICE.

LOUIS SANDERS, OF NEW YORK, N. Y.

DESIGN FOR A BELT.

SPECIFICATION forming part of Design No. 33,896, dated January 8, 1901.

Application filed December 18, 1900. Serial No. 39,789. Term of patent 3½ years.

To all whom it may concern:

Be it known that I, LOUIS SANDERS, a citizen of the United States, and a resident of the city of New York, borough of Brooklyn, in the county of Kings and State of New York, have invented and produced a new and original Design for a Belt, of which the following is a specification, reference being had to the accompanying drawing, forming a part thereof, in which is shown a perspective view of a belt embodying the features of my design.

The leading feature of the design consists in the transverse plaiting effect on the outer face of the belt.

15 The minor feature of the design consists

in the alternately-arranged plain and plaited panels, the plaits in the plaited panels overlapping each other.

Having thus described my invention, I claim as new and desire to secure by Letters 20 Patent—

The design for a belt as herein shown and described.

In testimony whereof I have signed my name to this specification in the presence of 25 two subscribing witnesses.

LOUIS SANDERS.

Witnesses:

J. FRED. ACKER,
JNO. M. RITTER.
